SUBCALIBER ADAPTER

James V. Dunham, Jenkintown, Pa.

Application November 7, 1949, Serial No. 126,003

4 Claims. (Cl. 102—41)

(Granted under Title 35, U. S. Code (1952),
sec. 266)

1

The invention described herein may be manufactured and used by or for the Government for governmental purposes without the payment of any royalty thereon.

My invention relates broadly to subcaliber projectiles, and particularly to a means of adapting any given size of small or large caliber cartridge case to accommodate a subcaliber projectile in the form of a spherical pellet or conventional pointed bullet, missile or the like.

Recent developments in "wound ballistics" (i. e. the science relating to the examination of causes and effects, preventive measures and remedies of human wounds caused by bullets and other fired projectiles) and other forms of research dealing with high velocity missiles have made it necessary to provide a quick, inexpensive yet efficient means of adapting any given size cartridge case to accommodate a subcaliber projectile which must have an unusually high muzzle velocity when fired. My invention, which is easy to make, very inexpensive, yet highly effective, and by virtue of which the projectile is given a comparatively high muzzle velocity, is highly adaptable for use in the previously mentioned study of wound ballistics and other fields of research.

Previous to my present invention the art had known of numerous methods for adapting a cartridge case of given size to accommodate a subcaliber projectile, most of which methods had drawbacks which my development has overcome. One of the most popular prior art devices, for example, employed a removably mounted sabot of wood or like material mounted in the case. The sabot inclosed the projectile and was discharged from the weapon's barrel along with the projectile upon firing the round. A typical example of this convention device is shown in U. S. Patent 636,375 to Wheeler wherein is disclosed a sabot that divides into fragments and becomes separated from the projectile after both leave the gun's barrel. Such sabots affect the trajectory of the projectile and decrease its normal accuracy. In addition, because the sabots tend to veer in erratic, unpredictable paths away from the projectiles trajectory, a hazard is presented to personnel and equipment in the vicinity.

Another old method of adapting a cartridge case to accommodate a subcaliber projectile necessitated that a resizing operation be performed on the open end of the cartridge case. Obviously this method took much time and was quite costly because it required the use of expensive dies, tools, and machinery.

2

As the following description will make clear, my invention obviates the above-described disadvantages of the forerunners in its field, and at the same time possesses additional superior characteristics hitherto unknown to those experienced with the prior art.

Broadly stated, then, the object of the present invention is to provide a simple and inexpensive means for adapting cartridge cases of any given caliber to accommodate lesser caliber projectiles and make it possible to impart a comparatively high muzzle velocity to the projectile.

Another object is to provide a means for adapting cartridge cases of any given caliber to accommodate lesser caliber projectiles without the need for a sabot and without the necessity of performing the conventional "necking down" of the cartridge case.

To obtain the foregoing and other objects and advantages of my invention, I provide an especially shaped, substantially cylindrical insert for addition to a cartridge case of any given caliber having the usual primer and propellant powder charge. By frictional resistance, or other means the insert holds a projectile which is the only object shot from the firearm when the cartridge is discharged, the cylindrical insert remaining behind in the cartridge case. As earlier mentioned the projectile may be in the form of a spherical pellet or the conventional pointed bullet, missile, or the like. However, for the sake of simplicity this specification will concern the spherical pellet.

A clearer understanding of my invention will be gained from an inspection of the following specification and the appended drawings wherein:

Fig. 1 is a view, partly in cross section, of a simplified form of my invention as applied to one type of conventional cartridge case;

Fig. 2 is a similar view of another form of my invention as applied to a second type of conventional cartridge case; and

Fig. 3 is a side view, partly in section, showing the Fig. 2 representation of my invention in position for firing within a firearm of conventional design.

Note that Fig. 1 shows one form of my invention as applied to a cylindrical cartridge case, and that Fig. 2 shows another form of my invention as applied to a conventional necked cartridge case. Either form of my invention, however, may be used in either type cartridge case and, as will later be made obvious, still other embodiments of my invention may be employed in

the two illustrated cases and also in many other designs of cartridge cases.

Referring to Fig. 1, in practicing my invention I provide a cylindrical plug 6 having a flat face 7 at one end (to the reader's right) and a dished face 8 at its opposite end (to the reader's left). Extending axially through the plug is a cylindrical opening comprising a ball chamber 9 which extends from the plug's flat face 7 a substantial distance toward its dished face 8, and a smaller diameter opening 10 which proceeds from the plug's dished face 8 and extends into ball chamber 9, forming the shoulder 11 at the juncture therewith.

Accommodated in ball chamber 9 and retained there by frictional resistance or other means is a spherical projectile 12 made of steel or other like material, the depth of the ball chamber 9 being sufficient to properly seat the projectile.

Cylindrical plug 6 is intended to be press fitted, flat face 7 outward, into the open, mouth end 13 of a conventional cartridge case 14 charged with propellant powder 15 and equipped with a primer (not shown) in its head end 16. On pressing plug 6 into place in cartridge case 14, flat face 7 of the plug is made coplanar with the open, mouth end 13 of the cartridge case, as Fig. 1 shows. As can also be seen in Fig. 1, spherical projectile 12 abuts shoulder 11 which limits the depth of the insertion. Projectile 12 also prevents escape of propellant powder 15 therepast.

In order to fire the Fig. 1 cartridge, it is placed into a suitable firearm (not shown) so that flat face 7 of plug 6 is held firmly against a similar flat face (not shown) on the firearm's barrel in order to prevent unwanted escape therepast of gas pressure resulting from ignition of propellant charge 15. The contact of these two faces acts as a seal to assure that the full force of the propellant powder will be used only in propelling spherical projectile 12 from the firearm. Upon firing cartridge 14, the full energy from powder charge 15 is directed by dished face 8 of cylindrical plug 6 into opening 10, thence against spherical projectile 12. As a result, when the projectile moves out of ball chamber 9 and along the smooth bore of the firearm's barrel (not shown), it is accelerated to such a degree that by the time the projectile has reached the firearm's muzzle (not shown) the projectile has acquired a comparatively high velocity.

In discussing the application of my invention to adapting the necked cartridge case for accommodating a spherical projectile, reference will be made to Fig. 2 which illustrates another form of my invention.

As there shown I have provided an essentially cylindrical plug 17 consisting of a head portion 18 and a neck portion 19, the two forming at their juncture a shoulder 20. Projecting from the face 21 of head portion 18 is a boss 22 having a flat face 23. Beginning from this flat face and extending axially inward (to the reader's left) through plug 17 is a central opening consisting of a cylindrical ball chamber 24, a smaller diameter cylindrical throat portion 25 which forms at the juncture therewith a shoulder 26, and an expanding, funnel-like mouth portion 27 which terminates at the end of neck portion 19 of plug 17.

Accommodated in ball chamber 24 and retained there by slight frictional resistance is a spherical projectile 28 made of steel or other like material, the depth of the ball chamber 24

75

being sufficient to properly seat the projectile 28.

Plug 17 is intended to be press fitted, neck portion 19 first, into the open, mouth end 29 of a conventional, necked cartridge case 30 having a tapered portion 31, a head end 32 equipped with a primer (not shown), and a charge of propellant powder 33. When plug 17 is inserted into the cartridge case 30 until shoulder 20 abuts mouth end 29 of the case, the wall of funnel-like mouth portion 27 of plug 17 is substantially continuous with the inside wall of tapered portion 31 of cartridge case 30. As in the Fig. 1 form of my invention, spherical projectile 28, held in place by slight frictional resistance, rests against shoulder 26 which limits the depth of its insertion. Projectile 28, in addition, prevents escape of propellant charge 33 out of throat portion 25 of plug 17.

The following discussion will be devoted to describing the operation of my novel ammunition, reference being made to the Fig. 3 showing which illustratively depicts the Fig. 2 cartridge after it has been placed in a suitable firearm consisting of a breech 34, a barrel 35 having the axial opening 36 and a smooth bored liner 37 having the smooth, axial opening 38. Examples of such firearms may be seen in U. S. Patents 834,341 to Tucker, 1,126,294 to Saffold, 2,342,684 to Nelson, etc. Breech 34 typically contains a chamber 39 which accommodates my uniquely modified cartridge. Barrel 35 is threadedly attached to breech 34 at 40, and liner 37 is secured within barrel 35 (by means not shown) so that the rear faces of the barrel and of the liner are coplanar. Liner 37 carries at the reader's left end a recess 41 which accommodates boss 22 of plug 17.

The firearm is loaded by inserting the modified cartridge, neck end first, into chamber 39 from the breech end until face 21 of head portion 18 of plug 17 rests against the surface formed by the rear faces of the barrel and liner, boss 22 slidably fitting into recess 41 in liner 37.

By conventional means such as a breech block (not shown) the cartridge case is secured into position, ready to be fired. After proper aiming, the primer (not shown) is detonated by any conventional means (also not shown) exploding propellant charge 33 in the usual fashion. Gas pressure generated thereby is prevented from leaking past the juncture of the case with the barrel by the seating of face 21 and boss 22 in the firearm, and is directed by tapered portion 31 of cartridge case 30 and by funnel-like mouth portion 27 (see Fig. 2) against the spherical projectile. This gas pressure forces the sphere with great velocity from chamber 24 in through bore 38 of the liner and out of the firearm.

Because of the closeness of contact between boss 22 and recess 41, face 21 of plug 17 and the surface formed by the coplanar rear ends of barrel 35 and its liner 37, and further because of the closeness of contact between cartridge case 30 and chamber 39 in breech 34, the maximum amount of energy derived from explosion of powder 33 is used in moving the projectile toward the muzzle end of the barrel 35.

From the foregoing it will be apparent that I have provided a simple and inexpensive means for adapting cartridge cases of a given caliber to accommodate lesser caliber projectiles, which means results in imparting a comparatively high muzzle velocity to the projectile; and that I have provided a means for adapting cartridge cases to accommodate lesser caliber projectiles without

resorting to the use of a sabot and without the necessity for performing a "necking down" of the cartridge case.

Those skilled in the art will realize that many variations and manifestations of my invention are possible without departing from its original scope and spirit. For that reason, I do not wish to be limited to the narrow limits of the applications as here shown by way of illustration only.

I claim:

1. A subcaliber adapter for a conventional cartridge case, comprising a cylindrical plug consisting of a neck portion which is press-fitted into the mouth end of the case, a head portion protruding from the case, and a shoulder at the juncture of the head and neck portions which abuts with and seals off the open case end, said plug having therethrough an axial opening which has a smaller diameter facing the interior of the case and a larger diameter leading to the case exterior, and a ring-shaped boss projecting from said plug head portion for mating with the chamber and rear barrel end of a firearm to prevent leakage of powder gases emanating from the case past the subcaliber projectile fired through the barrel.

2. The subcaliber adapted of claim 1 in which the cylindrical plug has a funnel-shaped opening whose narrowed mouth is confluent with the smaller diametered portion of the axial opening whereby to aid in converging the powder gases and facilitate their flow from within the case out through the plug's axial opening.

3. A cartridge having a subcaliber projectile, comprising: a conventional cartridge case; a cylindrical plug consisting of a necked portion which is press-fitted into the mouth end of the case, a head portion protruding from the case, and a shoulder at the juncture of the head and neck portions which abuts with and seals off the open case end, said plug having therethrough an axial opening; and a ring shaped boss projecting from said plug head portion for mating with the chamber and rear barrel end of a firearm to prevent leakage of powder gases emanating from the case past the subcaliber projectile fired through the barrel.

4. The cartridge of claim 3 in which the cylindrical plug has a funnel-shaped opening whose broadest portion opens into the cartridge case and whose narrowed mouth is confluent with the rearmost portion of the plug's axial opening, whereby to aid in converging the powder gases and facilitate their flow from within the case out through the plug's axial opening.
